UNITED STATES PATENT OFFICE.

JOHN A. WALDBURGER, OF MCKEESPORT, PENNSYLVANIA, ASSIGNOR TO FORTER-MILLER ENGINEERING COMPANY, OF MCKEESPORT, PENNSYLVANIA, A CORPORATION OF PENNSYLVANIA.

GAS-PRODUCER.

992,523.

Specification of Letters Patent. Patented May 16, 1911.

Application filed December 31, 1909. Serial No. 535,798.

To all whom it may concern:

Be it known that I, JOHN A. WALDBURGER, a citizen of the United States, residing at McKeesport, in the county of Allegheny and 5 State of Pennsylvania, have invented certain new and useful Improvements in Gas-Producers, of which the following is a specification, reference being had therein to the accompanying drawing.

10 My invention consists of an improvement in gas producers, more especially the class of water-seal gas producers, and refers particularly to means for agitating and discharging ashes from the lower portion of 15 the producer.

The invention consists of a rotatable hearth having laterally arranged wings so arranged as to sweep the ashes outwardly in a lateral direction into annularly arranged receiving cavities on the foundation and also into receiving vessels or chambers, below the water level, as shall be more fully hereinafter described.

Referring to the drawings:—Figure 1 is 25 a vertical sectional view of the lower portion of a gas producer constructed in accordance with my invention indicated on the line I, I, of Fig. 3. Fig. 2 is a detail sectional view of one of the sweeping blades 30 indicated by the sectional line II, II, of Fig. 1. Fig. 3 is a horizontal sectional view indicated by the line III, III, of Fig. 1. Figs. 4 and 5 are detail sectional views illustrating inclined arrangements of the sweeping 35 blades, indicated by the section lines IV, IV, and V. V. of Fig. 1.

The producer 2, as shown in the drawings, is usually cylindrical in cross section provided with the customary charging hopper, having suitable feed mechanism and gas outlet, and if desired, any convenient mechanism for stirring the contents (not shown), although the latter feature is not necessarily essential.

45 3 is an annular wind box surrounding the base portion of the producer immediately below its walls and provided with numerous inwardly disposed air ports of well known construction.

50 4 is a centrally arranged cone mounted on the hollow post 5, in connection with air supply mechanism and adapted to deliver volumes of air and steam laterally toward the outer portion of the charge.

55 6 is a stationary hearth located centrally

at the base portion of the producer, of coniform shape, whereby its supporting faces taper downwardly and outwardly toward the surrounding receiving cavities 6^a, 6^a, at opposite sides of the stationary hearth, said 60 cavities being partly annular in form, between the edge of the stationary hearth and the base wall 7 of the producer structure.

8, 8 represent water-sealed compartments for the reception of the ashes, into which 65 they may be delivered, or receiving buckets, or suitable vessels 9 may be set therein between the ends of annular cavities 6^a and below the level thereof for the same purpose. Said vessels may be removed when 70 filled and re-inserted, or the ashes may be withdrawn from the pits 8 in the usual way. The cavities 8 contain water as shown, the seal being effected by downwardly extending partitions 7' below the level of the bottoms 75 of cavities 6.

Rotatably mounted upon the upper face of the stationary hearth 6, is a correspondingly coniform shaped open frame or spider 10, centrally journaled around pipe 5, of any 80 suitable construction, as an open casting having approximately radially arranged arms 11 and a surrounding annular ring 12 with intervening open spaces. Above said ring 12, and connected therewith at intervals by vertical annular posts 13, is a supporting ring 14 mounted by an annular flange 15 and rolling bearings 16, upon an annular supporting ledge or flange 17 secured within the casing 7. The said ring 90 is provided upon its upper face with gear teeth 18 into which, at any suitable point, meshes a driving pinion 19 actuated by any suitable gearing or driving mechanism, not necessary to be described in detail.

Extending upwardly from arms 11 of the rotatable spider 10 across the vertical distance intervening between it and the lower edge of the inner terminal ring 20 of the producer below the air supply structure, are 100 a series of ash discharging wings 21, while at any suitable point or points, and preferably at two opposite positions, the wings 21' are extended outwardly and downwardly across and into the annular spaces 6^a, by 105 means of wing extensions 22. Said wing extensions, as shown in Fig. 1, practically fill said annular space as the spider 10 rotates so as to sweep the ashes therein along the bottoms of the ledges of the foundation 110

and of cavities 6^a into the chambers 8, or receptacle 9, as shown in Fig. 3. Wings 21 and 21' are arranged in a generally radial position, but at a slight inclination from a true radial arrangement, so that as the spider 10 rotates in the direction of arrow a, these wings will carry the ashes which have been deposited downwardly upon the stationary hearth around and outwardly upon the receiving bottom of the cavity 6^a, the wing extensions 22 sweeping around at intervals, carrying the ashes therein deposited into the chamber or vessel as stated.

It will be understood that the rotatable hearth is actuated at comparatively slow speed and as it performs its functions the upper edges of the wings will gradually dislodge the ashes from above to effect their fall so that the necessity of any poking or stirring of the fuel in combustion is largely or altogether obviated. The speed of rotation of the movable spider may be easily regulated as desired, and in proportion to the charge of coal in the producer.

While the wings 21, 21', and 22 may ordinarily be vertically disposed with good results, they may also be inclined forwardly toward their lower edges, as shown in Figs. 3 and 4, whereby the wings 21^a will more effectually engage the ashes lying on the sloping surface of hearth 6 or wings 22^a will easily scoop the ashes along the bottom of cavities 6^a and into water sealed chamber 8 or vessel 9. It will be observed that all of the ash supporting surfaces are above the water level and effectually sealed from the outside by the downwardly extending partitions 7.

It will be understood that the design or arrangement of the rotatable spider, discharging wings, and the other several features or details of construction may be changed to suit different conditions of use, but all such changes are to be considered as within the scope of the following claims:—

What I claim is

1. A gas producer provided with a stationary hearth, a rotatable spider lying upon and conforming to the surface thereof having ash-discharging wings radially separated from each other by intervening segmental openings, and means independent of the hearth for rotating the spider.

2. A gas producer provided with a stationary hearth, a rotatable spider composed of a central portion and arms extending generally radially therefrom lying upon and conforming to the surface of the hearth and provided with ash-discharging wings radially separated from each other by intervening segmental openings, and means independent of the hearth for rotating the spider.

3. A gas producer provided with a stationary coniform hearth, a rotatable spider

composed of a central pivoting portion and downwardly and outwardly sloping arms extending generally radially therefrom lying upon and conforming to the surface of the hearth and provided with ash-discharging wings radially separated from each other by intervening segmental openings, and means independent of the hearth for rotating the spider.

4. The combination with a gas producer having a stationary coni-form hearth and a surrounding ash receiving channel, of a centrally pivoted rotatable spider lying upon and conforming to the surface thereof and having ash-discharging wings extending generally radially from the central portion and radially separated from each other, said spider having outwardly and downwardly extending shifting extensions projecting into the ash receiving channel.

5. The combination with a gas producer having a stationary coni-form hearth and surrounding annularly recessed ash receiving channels, of a centrally pivoted rotatable spider lying upon and conforming to the surface of the hearth and having ash discharging wings extending generally radially from the central portion and radially separated from each other, some of said wings having outwardly and downwardly extending shifting extensions deflected forwardly at their lower portions, and operable through said channels, substantially as set forth.

6. The combination with a gas producer having a stationary coni-form hearth and surrounding annular ash receiving channels below the level thereof, of a centrally pivoted rotatable spider lying upon and conforming to the surface of the hearth and having ash discharging wings extending generally radially from the central portion and radially separated from each other, an annular trackway located above the outermost portion of the hearth, a series of rolling bearings thereon, and a supporting ring having an annular flange resting on said rolling bearings, substantially as set forth.

7. The combination with a gas producer having a stationary coni-form hearth and surrounding annular ash receiving channels below the level thereof, of a centrally pivoted rotatable spider lying upon and conforming to the surface of the hearth and having ash discharging wings extending generally radially from the central portion and radially separated from each other, a series of annularly arranged rolling bearings therefor, and means for supporting and rotating the spider on said bearings independent of the hearth, substantially as set forth.

8. A gas producer provided with an ash-receiving hearth, an annular ash receiving chamber below the level thereof, and a rotatable spider provided with ash-discharging wings adapted to deliver the ashes into

said annular chamber, and having supplemental downwardly extending radial wings adapted to discharge the ashes from said annular chamber into a receiving vessel or cavity.

9. In a gas producer, the combination with the producer structure, of a centrally arranged coni-form hearth, annularly disposed surrounding ash receiving channels below the hearth, water sealed chambers intervening between the terminals of said channels

and below the level thereof, and a rotatable spider mounted on said hearth and conforming to the surface thereof having ash moving members extending into said channels, substantially described.

In testimony whereof I affix my signature in presence of two witnesses.

JOHN A. WALDBURGER.

Corrections in Letters Patent No. 992,523.

It is hereby certified that in Letters Patent No. 992,523, granted May 16, 1911, upon the application of John A. Waldburger, of McKeesport, Pennsylvania, for an improvement in "Gas-Producers," errors appear requiring correction as follows: In the grant and in the heading of the printed specification the residence of the assignee is erroneously given as "McKeesport, Pennsylvania," whereas said residence should have been given as *Pittsburg, Pennsylvania*; and on page 2, line 53, the word "heart" should read *hearth*; and that the said Letters Patent should be read with these corrections therein that the same may conform to the record of the case in the Patent Office.

Signed and sealed this 18th day of July, A. D., 1911.

[SEAL.]

E. B. MOORE,

Commissioner of Patents.

said annular chamber, and having supplemental downwardly extending radial wings adapted to discharge the ashes from said annular chamber into a receiving vessel or cavity.

9. In a gas producer, the combination with the producer structure, of a centrally arranged coni-form hearth, annularly disposed surrounding ash receiving channels below the hearth, water sealed chambers intervening between the terminals of said channels

and below the level thereof, and a rotatable spider mounted on said hearth and conforming to the surface thereof having ash moving members extending into said channels, substantially described.

In testimony whereof I affix my signature in presence of two witnesses.
